(57) **CLAIM**

The ornamental design for a hair iron-dryer holder, as shown and described.

DESCRIPTION

FIG. 1 is an exploded perspective view of my new design of a hair iron-dryer holder.

FIG. 2 is a front view thereof.

FIG. 3 is a rear view thereof.

FIG. 4 is left end view thereof.

FIG. 5 is a right end view thereof.

FIG. 6 is a top view thereof; and,

FIG. 7 is a bottom view thereof.

The broken-line disclosure in the views is for illustrative purposes only and forms no part of the claimed design.
